(57) **CLAIM**

The ornamental design for a combined tamper-resistant in-wall duplex receptacle with USB charging ports and interchangeable face covers, as shown and described.

DESCRIPTION

FIG. 1 is a front perspective view of the combined tamper-resistant in-wall duplex receptacle with USB charging ports and interchangeable face covers;

FIG. 2 is an exploded view thereof;

FIG. 3 is a front plan view of the USB receptacle portion of the combined tamper-resistant in-wall duplex receptacle with USB charging ports and interchangeable face covers shown in FIG. 2;

FIG. 4 is a top perspective view of the USB receptacle portion of the combined tamper-resistant in-wall duplex receptacle with USB charging ports and interchangeable face covers;

FIG. 5 is a top plan view of the USB receptacle portion of combined tamper-resistant in-wall duplex receptacle with USB charging ports and interchangeable face covers;

FIG. 6 is a left side view of the USB receptacle portion of the combined tamper-resistant in-wall duplex receptacle with USB charging ports and interchangeable face covers;

FIG. 7 is a right side view of the USB receptacle portion of the combined tamper-resistant in-wall duplex receptacle with USB charging ports and interchangeable face covers;

FIG. 8 is a bottom view of the USB receptacle portion of the combined tamper-resistant in-wall duplex receptacle with USB charging ports and interchangeable face covers;

FIG. 9 is a front plan view of the combined tamper-resistant in-wall duplex receptacle with USB charging ports and interchangeable face covers of FIG. 1;

FIG. 10 is a back side view thereof;

FIG. 11 is a top side view thereof;

FIG. 12 is a bottom side view thereof;

FIG. 13 is a left side view thereof; and,

FIG. 14 is a right side view thereof.

In the drawings, the broken lines are for the purpose of illustrating portions of the combined tamper-resistant in-wall duplex receptacle with USB charging ports and interchangeable face covers and form no part of the claimed design.
